US0D1055954S

(12) **United States Design Patent** (10) **Patent No.:** **US D1,055,954 S**
(45) **Date of Patent:** **** Dec. 31, 2024**

(54) **DISPLAY SCREEN OR PORTION THEREOF
WITH GRAPHICAL USER INTERFACE**

(71) Applicant: **Safie Inc.**, Tokyo (JP)

(72) Inventor: **Masayuki Fujisawa**, Tokyo (JP)

(73) Assignee: **Safie Inc.**, Tokyo (JP)

(**) Term: **15 Years**

(21) Appl. No.: **29/883,751**

(22) Filed: **Feb. 2, 2023**

(30) **Foreign Application Priority Data**

Aug. 2, 2022 (JP) ..... 2022-016504 D

(51) **LOC (14) Cl.** **14-04**

(52) **U.S. Cl.**

USPC **D14/485**; D14/491

(58) **Field of Classification Search**

USPC D14/489-495, 485-488

CPC G06F 3/048-04897; H04M 1/724-72484

See application file for complete search history.

(57) **CLAIM**

The ornamental design for a display screen or portion thereof with graphical user interface as shown and described.

DESCRIPTION

The sole FIGURE is a front view of a display screen or portion thereof with graphical user interface showing my new design.

The peripheral broken lines depict a display screen or portion thereof, which form no part of the claimed design. The interior broken lines depict boundaries within which the claimed design is illustrated. The portion between the peripheral broken lines and the interior broken lines forms no part of the claimed design.

1 Claim, 1 Drawing Sheet
